BRACKET

Harry B. Goodman, Bellmore, N. Y.

Application August 14, 1946, Serial No. 690,439

5 Claims. (Cl. 248—264)

1

This invention relates to brackets and more particularly to adjustable brackets for the support of bars, rods, cornices, facial boards and like supports and accessories of shades, curtains, Venetian blinds and similar devices.

An important object of the invention is to provide a novel bracket which may be adjusted to accommodate and retain, for example, Venetian blind head bars having slots of various depths, and cornices or facial boards of various lengths.

Another important object is to provide a new bracket which may be adjusted to position a cornice or facial board at various distances from a Venetian blind head bar.

Still another object is to provide a bracket, adapted to position a rod or pole for a curtain at various distances from a cornice and/or head bar, and to accommodate itself to rods, poles, head bars and cornices of various lengths.

A further object is to provide a bracket from which a head bar, pole, rod or cornice may be readily removed or replaced, without removing or replacing any of the others.

Other objects and advantages of the invention will be apparent during the course of the following detailed description of the invention, taken in connection with the accompanying drawings, forming a part of this specification, and in which drawings:

Fig. 1 is a perspective view of the various portions (disassembled) of one form of the novel bracket.

Fig. 2 is a perspective view of the same, assembled, attached to a support, and supporting a head bar and a pole or rod.

Fig. 3 is a vertical section, substantially on the line 3—3 of Fig. 1 but including the head bar of Fig. 2.

Fig. 4 is a top plan of two of the novel brackets of Figs. 1 to 3 inclusive, attached to a support (in horizontal section) and supporting a head bar, rod or pole, and a cornice.

Figs. 5 and 6 are perspective views of a modification of the bracket, disassembled in Fig. 5 and assembled in Fig. 6, attached to a support, supporting a head bar and in position to receive a cornice.

In the drawings, wherein for the purpose of illustration are shown a preferred and a modified form of the invention, and wherein similar reference characters designate corresponding parts throughout the several views, the letter A designates one form of the bracket invention; the letter B, another form; C, a support for the

2

bracket A; D, a head bar; E, a rod and F a cornice, both supported by the bracket A; and G a support for the bracket B.

The novel bracket A is shown particularly in Fig. 1 and comprises a first or support-attached and head-bar-supporting portion 10, a second or slidably adjustable portion 11, slidably secured to the portion 10, a third or rod-supporting portion 12, slidably secured to the portion 11, and a fourth or cornice-supporting portion 13, slidably carried by the portion 12.

This first or support-attached and head bar-supporting portion 10, includes a substantially flat plate 15, having a vertically-disposed flange 16 extending from its rear end to form, with the plate 15, substantially a right angle. The plate 15 is provided with means to cooperate with means carried by the portion 11 to slidably connect the two, and may be the walls of horizontally-disposed pairs of perforations 17 and 18, while the flange 16 may have several perforations 19 for insertion of suitable means to secure the portion 10 to a support C. Secured to the plate 15, as by welding or soldering, is a horizontally-extending head bar-supporting ledge or flange 20 which, preferably, extends the width of the plate 15, to the flange 16, and has a preferably narrow slot 21 intermediate its ends and disposed along its juncture with the plate 15. Slidable vertically through the slot 21 is a means 22 to detachably connect a head bar D to the portion 10. This means preferably comprises a slide member having an elongated intermediate portion 23 slideable through the slot 21, and having an upper offset 24 and a lower offset 25, both forming substantially right angles with the intermediate portion 23. Both offsets prevent the portion 23 from dropping out of the slot 21 and the offset 24 has another function to be subsequently described.

As for the second or slidably adjustable portion 11, this preferably comprises a single sheet of suitable rigid material, bent or otherwise formed to provide two substantially flat plates 26 and 27 forming a right angle. The plate 26 is provided with means to cooperate with the means (walls of the pairs of perforations 17 and 18) to adjustably connect the portions 10 and 11, and this may be the walls of horizontally-disposed slots 28 and 29. Any desirable fasteners may be employed such as bolts, with their shanks inserted through the perforations 17 and slot 28, and perforations 18 and slot 29, with suitable nuts upon the shanks. The plate 27 is provided with means to cooperate with means carried by

the portion 12 to adjustably connect the portions 11 and 12, and the former may be the walls of horizontally-disposed pairs of perforations 30 and 31.

The third or rod-supporting portion 12 preferably also comprises a single sheet of suitable rigid material, bent or otherwise formed to provide two substantially flat plates 32 and 33, forming a right angle. The plate 32 has means to cooperate with the walls of the perforations 30 and 31 to adjustably secure the portions 11 and 12 together, comprising the walls of horizontally-disposed slots 34 and 35 and through these perforations 30 and slot 34 and perforations 31 and slot 35 may be inserted bolts, with suitable nuts thereon, such as shown at 36 and 37 respectively in Fig. 2. Carried upon the inner face of the plate 33 is a rod-supporting means 38 such as a short, trough shaped member 39 preferably disposed adjacent the upper end 40 of the plate, which end projects slightly above the horizontal plane of the upper edge of the plate 32 for a purpose to be detailed. Now, as for the fourth or cornice-supporting portion 13, this also preferably comprises two substantially flat plates 41 and 42, which may be joined together as by a curved juncture section 43 with the plates 41 and 42 normal to each other. The plate 41 is provided with means to adjustably connect the portion 13 with the portion 12 in cooperation with sections of the portion of the latter, and may comprise a downturned upper flange 44 and an upturned lower flange 45, both spaced from and paralleling the plate 41. The upper end 40 of the plate 33 is adapted to extend into the slot formed by the flange 44 and adjacent section of the plate 33 while the lower end of the same plate is adapted to extend into the slot formed by the flange 45 and adjacent section of the plate 33. In fact, the flanges 44 and 45 may be continued flat against the plate 42 to provide strengthening means for the plate 42 for receiving an end portion of a cornice F, as may be seen in Fig. 4.

The upwardly-extending upper end 40 causes the portion 13 to extend above the horizontal planes of the upper edges of the portions 10, 11 and 12 and this tends to conceal the upper parts of these portions 10, 11 and 12 when a cornice is in place.

It should be understood that there are both left-hand brackets A as well as right-hand brackets A, as is apparent in Fig. 4, and similar reference characters designate like parts of both the right-hand and left-hand brackets.

From the foregoing and from Figs. 2, 3 and 4 it is apparent how the novel brackets A are assembled, mounted and employed. The portion 10 is, of course, attached to the support C, as a portion of a window frame, as by screws, extending through the perforations 19 and into the support C. Mounting of the head bar E is effected by manipulation of the means 22 by raising the intermediate portion 23 thereof until the upper offset 24 clears the upper face 50 of the head bar D so that the latter may be disposed upon the flange 20 and the offset 24 dropped into the conventional upwardly-opening slot 51 of the head bar with the ends of the latter abutting or close to the inner faces of the plate 15.

Adjustably positioning the cornice F toward or away from the support C (as a window frame) is effected by the slots 28 and 29 and the desired length of the cornice is provided by adjustment effected by use of the slots 34 and 35.

The end of the rod E rests, of course, in the trough 39 and the conventionally flanged upper and lower parts of the end portion 52 of the cornice F slide over the upper and lower parts of the plate 42.

It will be noted in Fig. 2, that when the parts are assembled as therein shown, the free horizontal edge of the flange 44 is close to the upper edge of the trough 39. If the rod E is cut or adjusted to substantially abut the inner faces of the two opposite plates 33 of two brackets A, the rod E cannot be accidentally displaced after its ends are disposed within the troughs.

Gravity, of course, prevents the upper offset 24 from leaving the head bar slot 51 and thus retains the head bar D in place. Since the slots 51 vary in depth, the differences in depth are taken care of by the fact that the intermediate portion 23 of the means 22 is slidable through the slot 21.

Referring to the form B of the invention, shown in Figs. 5 and 6, this form is employed where a head bar D and cornice F are to be supported by the bracket 15 and as may be seen in Fig. 6, is attached, if desired, somewhat differently to a support G than is the bracket A to support C. The latter comprises two adjustably-connected portions 60 and 13.

The portion 60 corresponds somewhat with the portions 10 and 12 of form A but omits the means 38 of form A, and is a support-attached and head bar-supporting portion as well as the portion to which a cornice supporting portion is adjustably secured, this last being, preferably, substantially similar to the portion 13 of form A and similar reference characters are employed.

The portion 60 includes a substantially flat plate 61, having a vertically-disposed flange 62 extending from its rear end to form, with the plate 61, substantially a right angle. The flange 62 may be provided with several perforations 63 for insertion of suitable means to secure the portion 60 to a support, such as a support C. In addition, there may be provided other perforations 64 in the plate 61 for the insertion of suitable means, as screws, to secure the portion 60 to a support G. Carried by the plate 61, as by being welded or soldered thereto, is a horizontally-disposed ledge or flange 65 which, may extend to the flange 62, has a preferably narrow slot 66 intermediate its end and this slot extends along the juncture of the flange 65 and plate 61. Slidable vertically through the slot 66 is means 67 to detachably connect a head bar D to the portion 10. This means preferably comprises a slide member having an elongated intermediate portion 68 slidable through the slot 66, an upper offset 69 and a lower offset 70 all for the same purposes as the portion 23 and offsets 24 and 25.

It will be noted that the forward end section of the plate 61 has an upwardly-extending edge portion 71 corresponding, in function, to the upper end 40 of the plate 33, and for a like purpose.

From the foregoing description of form B, coupled with the description of form A, it is obvious how form B is attached to a support and assembled, as in Fig. 6, with the head bar D and a cornice F supported thereby, with the cornice 70 disposed, because of the section 71, to conceal the upper parts of the portion 60.

Various changes may be made to the forms of the invention herein shown and described without departing from the spirit of the invention 75 and scope of the claims.

What is claimed is:

1. In a bracket, a support-attached portion, including a plate having an upper, horizontally-disposed edge, a cornice-supporting portion, means carried by the support-attached portion to support a head bar, and means carried by the support-attached portion to slidably receive the cornice-supporting portion, including a section extending upwardly above the horizontal plane of said edge, forwardly of said first mentioned means, and having substantially parallel faces, with a section of said cornice-supporting portion disposed about and in frictional contact with both of said faces.

2. In a bracket, a support-attached portion, including a plate having an upper, horizontally-disposed edge, a cornice-supporting portion, means carried by the support-attached portion to support a horizontally-disposed rod including a trough having an upper edge, and means carried by the support-attached portion to slidably receive the cornice-supporting portion, including a section extending upwardly above the horizontal plane of said upper, horizontally disposed edge, and having substantially parallel faces, with a section of said cornice-supporting portion disposed about and in frictional contact with both of said faces and normally above and closely adjacent said upper edge of said trough.

3. In a bracket, a first, support attached portion; a second, slidably adjustable portion, extending forwardly of said first portion, a third portion extending to one side of said second portion; a fourth, cornice-supporting portion, extending forwardly of said third portion, means carried by one of said portions to receive the end of a rod; means carried by said first and second portions for slidably adjusting said first and second portions toward and away from each other; means carried by said second and third portions for slidably adjusting said third portion to one side of said second portion; and means carried by said fourth portion for slidably adjusting said fourth portion toward and away from said third portion.

4. In a bracket, a first, support-attached portion; a second, slidably adjustable portion extending forwardly of said first portion; a third portion extending to one side of said second portion and having a section extending above the horizontal planes of said first and second portions, said section having substantially paral-

lel faces, and a rod-receiving trough below said section, said trough having an upper edge; a fourth, cornice-supporting portion; means carried by said first and second portions for slidably adjusting said first and second portions toward and away from each other; means carried by said second and third portions for slidably adjusting said third portion to one side of said second portion; and means carried by said fourth portion for slidably adjusting said fourth portion toward and away from said third portion, including a section disposed about and in frictional contact with both of said faces and above and closely adjacent said upper edge of said trough.

5. In a bracket, a first, support-attached portion; a second, slidably adjustable portion extending forwardly of said first portion; a third portion extending to one side of said second portion and having a section extending above the horizontal planes of said first and second portions, said section having substantially parallel faces, and a rod-receiving trough below said section, said trough having an upper edge with said edge immediately below said section; a fourth, cornice-supporting portion; means carried by said first and second portions for slidably adjusting said first and second portions toward and away from each other; means carried by said second and third portions for slidably adjusting said third portion to one side of said second portion; and means carried by said fourth portion for slidably adjusting said fourth portion toward and away from said third portion, including a section disposed about and in frictional contact with both of said faces and said last-named section having a downwardly-facing edge above and closely adjacent the rear portion of said upper edge of said trough.

HARRY B. GOODMAN.
